UNITED STATES PATENT OFFICE

CARL J. HALBORG, OF DETROIT, MICHIGAN, ASSIGNOR TO COLONIAL TOOL COMPANY,
OF DETROIT, MICHIGAN, A CORPORATION OF MICHIGAN

BROACH HOLDER OR ADAPTER

Application filed June 24, 1926. Serial No. 118,377.

The object of my invention is to provide a broach adapter which will carry various sized broaches having shanks of equal size, and which will permit broaches to be removed from and inserted in the adapter by quick and simple operation and thus avoid loss of time in changing tools and also avoid the necessity of providing a broach puller or adapter for each broach.

With these and other objects in view my invention consists in the arrangement, combination and construction of the various parts of my improved device as described in the specification, claimed in my claims and shown in the accompanying drawings, in which:

Fig. 1 is a longitudinal section of my device, showing in elevation the end of a broach inserted therein.

Fig. 2 is a side elevation of my device with certain parts broken away to show the broach end turned to released position in the holder.

Fig. 3 is a cross section taken on line 3—3 of Fig. 1.

I have shown a socket block 1 having a screw-threaded shank 2 adapted for engagement with power transmitting mechanism (not shown). In the center of the block 1 is cut a circular opening 4 adapted to receive in close fit the end of the broach 3. Intermediate the ends of the block 1 and on the opposite sides thereof, are cut openings 5 adapted to receive plugs 6. These openings 5 extend into the central opening 4 and together form a continuous opening running through the block at right angles to the opening 4. The openings 5 are formed with recesses 7 to receive corresponding shoulders on the plugs 6. The plugs 6 are of sufficient length so that when they are inserted in the openings 5 with their outer ends flush with the surface of the block 1, their inner ends extend into the opening 4. Those surfaces 9 of the inner ends of plugs 6 which face the inner end of opening 4 are cut in so that the surfaces 9 incline from the lower edges of plugs 6 toward the outer end of opening 4. Positioned in the sides of the block 1 carrying the openings 5 are screw studs 10 which serve, in connection with the washers 11, to secure to the block 1 the spring

fingers 12 which contact at their free ends with the outer ends of plugs 6 and serve to normally force plugs 6 into the openings 5 and to hold the outer ends of plugs 6 flush with the surface of block 1. The end of the broach 3 which is adapted to be inserted into the opening 4 is tapered on opposite sides adjacent its end as at 13, and has slots 14 undercut therein on the sides corresponding with the tapers 13, which slots are adapted to provide "hook" surfaces for engagement with parallel surfaces on the ends of the plugs 6. Those sides of the slots 14 which contact with the surfaces 9 of the plugs 6 are tapered to correspond with and to fit the surfaces 9 and so prevent the plugs 6 from being forced outwardly when the broach is being pulled. The outer edges of the opening 4 are cut as at 44 to permit easy insertion of the broach 3. The plugs 6 are of greater width than the diameter of the broach 3 and of the opening 4 as shown in Fig. 3.

The end of the broach 3 is inserted in opening 4 so that the tapered surfaces 13 will contact with the edges of plugs 6 and will raise the plugs 6, by cam action in the opening 5 and so cause the ends of plugs 6 to slide over the surfaces of the broach 3 and fall into the slots 14 which are cut into those sides of broach 3 which correspond with the tapered surfaces 13. When the broach is forced into the opening 4 as far as it will go, the plugs 6 will drop into the slots 14 and will be held in those slots by the action of the springs 12. The broach will then be secured in the block 1 ready for use. The broach 3 may be quickly and easily removed from the block 1 by giving the broach a quarter turn which causes the edges of the bottoms of the slots 14 to bear against the ends of the plugs 6 and force the plugs 6, by cam action, outward through the openings 5. The inner ends of plugs 6, when the full quarter turn of the broach 3 has been made, will be held flush with the sides of the opening 4 by the unslotted portion of the broach 3, and so permit the broach to be withdrawn from the block. The shoulders 8 formed on the plugs 6 fit into the recesses 7 and thus prevent the plugs from sliding through the openings 5.

into the block when the broach has been removed. In making the plugs 6 wider than the diameter of the broach 3 and of the opening 4 I have eliminated the possibility of the edges of the bottoms of the slots 14 (which are shaped for a cam effect, to release the broach upon a suitable rotation) binding upon the corresponding cam surfaces provided by the respective ends of the plugs 6 and preventing the broach from being turned to raise the plugs. I have, by cutting the slots 14 in those sides of the broach 3 corresponding to the tapered surfaces 13, eliminated the necessity of turning the broach in the opening 4 to permit the plugs 6 to drop into the slots 14 as when the broach is inserted in the opening 4 the tapered surfaces 13 contact with the ends of the plugs 6 and force them outwardly through the openings 5 until the inner ends of plugs 6 are clear of the opening 4 which permits the broach to be pushed into opening 4 until the slots 14 are directly under the openings 5 and in place to receive the plugs 6.

It is thus apparent that I have provided a broach puller or adapter in which broaches may be quickly and easily removed and replaced with minimum loss of time which is very important in production work.

It will be obvious that various changes may be made in the arrangement, combination and construction of the various parts of my improved device without departing from the spirit of my invention, and it is my intention to cover by my claims such changes as may be reasonably included within the scope thereof.

What I claim is:

1. In combination, a broach having a shank tapered on opposite sides of its end and transverse slots in those sides of the shank corresponding with the tapers on the end thereof, said slots having their sides nearest the tapered end diagonally cut to form an acute angle with the bottoms of said slots, and a broach holder comprising a block having an axial recess in one end thereof adapted to fit said broach shank, and having transverse openings in opposite sides thereof leading into said recess, the outer edges of said transverse openings having notches therein, plugs movable in said openings having lateral extensions thereon adapted to engage and fit in said notches, and having the inner rear faces thereof diagonally cut to fittingly engage the diagonally cut sides of the slots in said broach shank, spring members secured to the outer surface of said block and adapted to retain said plugs in said transverse openings, and to urge said plugs into engagement with said slots in said broach shank.
2. In combination, a broach having a shank having transverse slots in opposite sides thereof, forwardly inclined rear walls for said slots, and a holder having a central longitudinal opening therein adapted to receive

said shank and transverse openings leading into said central opening, plugs movable in said transverse openings having forwardly inclined rear faces adapted to engage the forwardly inclined rear walls of the slots in said shank, whereby the pull on said shank tends to draw said inclined faces and walls into deeper engagement.

3. In combination, a broach having a shank having transverse slots in opposite sides thereof, forwardly inclined rear walls for said slots, and a holder having a central longitudinal opening therein adapted to receive said shank and transverse openings leading into said central opening, plugs movably secured in said transverse openings and having forwardly inclined rear faces adapted to engage the forwardly inclined rear walls of the slots in said shank, said plugs being of less breadth than the width of said slots whereby said inclined faces may be disengaged by a rotary movement of the shank alone.

4. A device of the class described, for co-operation with a tool shank provided with slots presenting hook portions, comprising a block having an opening in the longitudinal center thereof and having openings in the sides thereof extending transversely through said longitudinal opening and each provided with a recess at an edge thereof, plugs movable in said side openings and extendable into said longitudinal opening for engaging and securing a tool shank therein, said plugs each having a shoulder which is adapted to fit in a mentioned recess provided at an edge of the corresponding openings, and said plugs having surfaces adjacent their inner ends so diagonally cut to form an acute angle with the adjacent surface of said longitudinal opening and to cooperate with said hook portion, springs mounted upon said block and positioned to bear upon the outer ends of said plugs for holding the same in said openings, and a shank secured to said block for engagement with power transmitting mechanism.
